(57) **CLAIM**

The ornamental design for a desktop centrifuge, as shown and described.

DESCRIPTION

FIG. 1 is a top perspective view of the design for a desktop centrifuge according to the present disclosure;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top perspective view with the lid open; and,

FIG. 9 is a bottom perspective view with the lid open.

The broken lines immediately adjacent the shaded areas represent the bounds of the claim, while all other broken lines are directed to environment and are for illustrative purposes only; the broken lines form no part of the claimed design.

1 Claim, 5 Drawing Sheets
